UNITED STATES PATENT OFFICE.

EDGAR W. KIRK AND JAMES F. HAZEL, OF KANSAS CITY, MISSOURI.

HYDRAULIC MOTOR.

SPECIFICATION forming part of Letters Patent No. 510,270, dated December 5, 1893.

Application filed September 29, 1892. Serial No. 447,342. (No model.)

To all whom it may concern:

Be it known that we, EDGAR W. KIRK and JAMES F. HAZEL, citizens of the United States, residing at Kansas City, in the county of Jackson and State of Missouri, have invented certain new and useful Improvements in Hydraulic Motors; and we do hereby declare that the following is a full, clear, and exact description of the same, such as will enable others to make and use the same, reference being had to the accompanying drawings, forming a part of this specification.

The objects of our invention are, first, in a water motor in which the frame of the machine is supported at the side upon floats to raise and lower the frame carrying the water actuated devices above and below the upper surface of the floats; second, to provide a sluice gate for the floats which may be operated in sections and more readily closed against the current; third, to increase and diminish the entrance of the water to the sluice between the floats; fourth, to regulate the force of the current diverted toward the sluice by the stationary wings; fifth, to enable the tension of the endless conveyers to be increased when submerged in the water; sixth, to decrease the resistance of the buckets in moving against the current; seventh, to operate automatically with the folding bucket an auxiliary bucket; eighth, to close the buckets when actuated by the current and stop the action of the machine; ninth, to prevent the shock upon the buckets in changing position for the action of the current thereon, and also to guard the buckets from ice and passing obstructions when the buckets are submerged in the water.

Our invention further consists in the novel construction and combination of parts such as will first be fully described and specifically pointed out in the claims.

In the drawings,—Figure 1. is a side view of the motor with the near float removed showing the inner side of the other float, the frame carrying the motor and its vertically moving supports, shown connected with broken portions of the near float; the means for controlling the action of the motor, the forward sectional sluice gate, the shields for the buckets and the wings connected with the inner float and its sectional parts. Fig.

2. is a plan view of the floats and motor. Fig. 3. is a vertical sectional view of the floats and motor taken upon the line x, x , of Fig. 1. Fig. 55 4. is a detail view of one of the stationary wings showing the grooved supports. Fig. 5. is a detail view of one of the movable journals for the rear shaft. Fig. 6. is a detail view in perspective of one of the self closing buckets 60 showing the auxiliary bucket and its self acting support.

Similar letters of reference indicate corresponding parts in all the figures.

In the construction of our invention, A. A'. 65 represent separate longitudinal hollow vessels or floats which are arranged the proper distance apart and placed in a parallel position in the river or other water course. The vessel or floats A. A'. are made the same 70 length so as to carry the motor hereinafter described in the sluice a^0 , between them, and each with a water tight compartment a , extending its entire length. The sides of each compartment a , consists of the top a' , inner 75 vertical sides a^2 , outer vertical sides a^3 , and bottom a^4 . The outer side a^3 , of each float at the extreme forward end is curved inwardly in the direction of the inner side a^2 , as at a^x , (see Fig. 2), so as to divert the current of 80 water from the said forward ends. To the top a' , of the float A. at a point near the rear end of said float is attached rigidly one end of a transverse connecting bar or beam B. the other end of which beam is attached rigidly 85 to the top a' , of the other float A'. near the rear end of said float. The forward end of the floats A. A'. are bound together by means of a rod C. one end of which rod is rigidly attached to the inner side of a float A. at its 90 extreme forward end and nearly in line with the top a' , of said float and the other end is attached in like manner to the inner side and forward end of the float A'.

To support the motor between its floats A. A'. a frame G is first made which consists of parallel rods d, d^x , one of which is arranged in position a short distance from and within the line of the inner side a^2 , of float A. and the other a like distance from the float A'. 100 The rods d, d^x , extend in length nearly to the beam B. in one direction and to a point two thirds of the length of the floats, toward the rod C. To the ends of the rods d, d^x , are

connected upright supports d' , d' , d' , d' , which extend a proper distance in height and to the upper ends of the supports d' , d' , are connected the ends of the horizontal rods d^2 , d^2 , which are arranged above and in a parallel position with the rods d , d^2 . The ends of the rods d^2 , d^2 , are bound together by transverse rods d^3 , d^4 , the rod d^3 , connecting the forward ends of the rods d^2 , d^2 , and the rod d^4 , to the rear ends of said rods. To one of the rods d^2 , near float A', at a point from its forward end a distance one third of its length in the direction of the rear end or toward the beam B. is attached an arm or bearing d^5 , which extends at right angles to said rod and in the direction of the top a' , of float A'. and a short distance past the inner side a^2 , of said float. Upon the same rod and at a point one third the distance from the rear end toward the forward is attached a similar arm or bearing b^6 . Upon the other rod d' , and directly opposite in position to the arm d^5 , is attached an arm d^7 , which extends in the direction of the top a' , of the float A. and a corresponding distance over said float. To the forward end of the rod d , and opposite in position to the arm d^5 , in rod d^2 , is attached a shaft hanger or bearing d^8 , which extends a short distance from said rod. In the inner side of the arm d^5 , on rod d^2 , is journaled one end of a driving shaft E. the other end of which shaft extends through the shaft hanger d^8 , on the rod d' , and also to a point within the inner side of the float A. over the top a' , of said float and between which inner side of float A. and the shaft hanger d^8 , on the shaft E. is fixed a power transmitting pulley F. over which is passed the cable f, for the purpose herein-after described.

Upon the inner side of the arm d^6 , is attached rigidly a horizontal slotted guide bearing, d^9 , (see Fig. 5.) and upon the inner side of the arm d^7 , is a similar slotted guide bearing, in which is journaled one end of a rotary shaft G. the other end of which shaft is journaled in the slotted bearing d^9 , on the arm d^6 . In the inner sides a^2 , of the floats A'. vertically in line with the ends of the arms d^5 , d^6 , are grooves a^6 , a^6 , the sides of which are separated from the compartment a, of the float and extend to the bottom a^4 , of said float. Through each one of the outer ends of the arms d^5 , d^6 , in a vertical direction is made an opening d^{10} . In the opening d^{10} , of the arm d^6 , is inserted a fixed bar H. upon the longitudinal edge of which in the direction of the forward end of the float are made the notches h. In a transverse direction to the bar H. are made the perforations h', which perforations are made at slight distances apart in the length of said bar. Said bar H. enters the groove a^6 , in the side of float A'. and extends a short distance above arm d^5 . In the opening d^{10} , of the arm d^6 , is inserted a similar fixed bar H. constructed in a like manner and of corresponding length. Through the arm d^5 , is an opening d^{12} , which is similar to

the opening d^{10} , in the arms d^5 , d^6 , and a similar fixed bar H. is arranged in said opening.

Upon the inner sides of the float A. in line with the inner end of arm d^7 , is a vertical groove a^6 , which is similar to the groove on the inner side of float A'. which receives the fixed bar H. upon said arm. The shaft E. which carries the pulley F. extends to a point nearly in line with the inner side of float A. and in the side of said float is made a vertical groove a^6 , opposite said end of said shaft similar to the groove a^6 , in the other float A'. Upon the inner end of shaft E. over the groove a^6 , is a journal bearing d^{14} , vertically through which is an opening d^{10} , and in which opening is a vertical fixed bar H. which is similar to the bar H. in the arms d^5 , d^7 .

Through the perforation h' , in bar H. beneath arm d^5 , is inserted horizontally a removable pin d^{15} , which extends beyond the inner line of the groove d^6 , and upon the top a' , of the float A'. This pin d^{15} , supports the weight of the end of the frame D. at said point. In the perforation h' , in bar H. on arm d^6 , is inserted a like pin d^{15} , and also in the bar on arm d^7 , and through the bar H. on bearing d^{14} , each pin resting upon the top a' , of the respective floats.

Upon the top of the float A'. near the groove a^6 , and upon the side of the bar H. in arm d^5 , having the notches h, is mounted a standard I. upon the upper end of which is a swinging fulcrum i, upon which swinging fulcrum is fulcrumed a lever K. Upon the top of the float near the other bar H. is a similar standard I. having also a swinging fulcrum and a lever K. and upon the other float at the side of each bar are like standards, swinging fulcrums and levers, the inner end of each of which lever engages with the notches h, in the bar H. so that the bars are raised or lowered thereby.

Upon the shaft E. are mounted two sprocket wheels L. L. of the requisite diameter and arranged a short distance apart. Upon the shaft G. are mounted the sprocket wheels M. M. of the same diameter. Over one of the sprocket wheels L. is passed one end of a sprocket chain N. which chain is extended over one of the sprocket wheels M. and the two ends of the chain connected together in the usual manner. Over the other sprocket wheel L. is passed a like sprocket chain which also passes over the other wheel M. on shaft G. and connected in like manner. To the outer side portions of sprocket chains are attached the buckets O. which are constructed as follows:—Transversely to the chains N. N. and to the outer side of said chains is attached a transverse plate o, the ends o', o', of which are bent downwardly at right angles. The scoop or the portion operated upon by the water consists of a flat plate O^x, of a considerable width, a portion of which is bent at right angles to form the sides o², o², the upper ends of which sides are pivotally attached to the inner sides of the bent portions o',

of the plate o , the sides o^2 being narrower at the lower ends than at the upper. The upper edge of the plate o^x , extends in line with the inner edge of the plate o . Upon the upper side of the plate o^x , is hinged so as to swing in both directions forward and backward, the lower edge of a flat plate P , which constitutes an auxiliary bucket and extends in length between the lines of the sprocket chains N . N .

10 To the upper edge of the plate o^x , is pivotally attached the lower end of a vibratory rod p , which rod extends through a vertical perforation o^4 , in the plate o , in rear of the plate or bucket P , the upper end p' , of which rod p , is bent forward in a curved line in a slight degree.

For the purpose of increasing the tension of the sprocket chains, a lever R . is fulcrumed at r , to the under side of the upper rod d^2 , of

20 the frame D . directly above the shaft G . and upon which shaft is a loose fitting collar g , to which collar is pivotally connected the lower end of the lever R . Upon the other side of frame D . is a similar lever which is

25 connected with the shaft G . in like manner. (See Fig. 5.) Upon the rod d^2 , is mounted a sector r , which is notched at r' to secure the said lever in position. Extending from the transverse rod d^3 , to the transverse rod d^4 ,

30 and beyond said rods, and attached in a parallel position to the rod d^2 , upon the upper side of the rods d^3 , d^4 , is a supporting bar or beam S . at each end of which beam is a grooved pulley s . Upon the rod d^2 , of frame

35 D . between the ends of said rod, is attached a short standard s' , and upon the rod s , transversely to said standard, is a standard s^2 , of an increased height to the standard s' . In the said standard s' , is journaled one end of a

40 horizontal rotating shaft s^3 , the other end of which shaft extends through the standard s^2 , and upon the end of said shaft is a crank s^4 . Upon the shaft s^3 , near the inner side of standard s^2 , is a ratchet wheel s^4 , and upon

45 the ratchet wheel on the upper end of the standard s^2 , is pivoted a panel s^5 , which engages at its lower end with the wheel s^4 . Upon the shaft s^3 , over the beam S . is a drum s^6 . Around drum s^6 , is wound a rope or chain

50 s^8 , one end of which chain extends over the pulley s , at one end of beam S . and the other end over the pulley s , at the other side of said beam. Between the forward standards d' , d' , of the frame D . and attached at both

55 sides in a horizontal position to said standards beneath the transverse rod d^3 , is a triangular shaped plate or shield U . one end of which extends in a direct line from a point above the sprocket wheels L . L . forward and

60 over the sluice a^0 , between the forward ends of the floats A . A' . as far as required and thence bent at an angle inwardly toward the sprocket wheels L . L . and the lower side inclined downwardly, to a point in line with

65 the inner side of rods d , d , and the proper distance from the sprocket wheels L . L . as will admit the passage of a bucket O . in a

closed position, between the lower side u' , and the said sprocket wheels. To the inner end of the shield U . above the wheels L . is attached 70 one end of a curved guide rod u^2 , which extends in an inwardly curved line in the path of the plate o^x , of each bucket O . and is attached at the other end to the lower end of the shield u' . Through the plate u , of the shield U . directly beneath the pulley s . on the forward end of beam S . is a perforation u^3 and in the plate u' , in a vertical line with the perforation u^3 , is a perforation u^4 through which extends one end of the chain s^8 . Below 80 beneath the series of buckets O . O . submerged in the water and extending in the sluice a^0 , from a point near the rear end of floats A . A' . forward, toward the sluice gates, is a bucket closing rod V . the forward end v , of which is bent at right angles and extended upward near plate u' , and connected with one end of the chain s^8 . The other end of chain s^8 , extends downwardly and is connected with the other or rear end of the rod V . To the 85 forward end of the floats A . A' . parallel in position to and below the rod G . and attached to the inner side a^2 . of each float are transverse rods C' , C^2 . the rod C' . being placed farther in rear of the vertical line through rod C . and the rod C^2 . a degree farther in rear of the vertical line through rod C' . The rod C^2 . is arranged a short distance above the line of the bottom a^4 , of the floats and the rod C' . equi-distant from said rod C^2 . and rod C . To 90 rod C . is pivoted the upper longitudinal edge of a sectional plate c^4 , of a sluice gate C^3 . which extends in length from a point near the inner side of one float A . to the inner side of the other float A' . and downwardly nearly to the 95 rod C' . To the rod C' . is pivotally attached a sectional plate c^5 , of the sluice gate C^3 . which is similar to the plate c^4 , and extends nearly to the rod C^2 . Upon the rod C^2 . is pivotally attached a sectional plate c^6 , which is also constructed in like manner to the plate c , and extends downwardly nearly to a point in line with the bottom a^4 , of the floats A . A' , within the sluice a^0 . Upon the float A . near the line of the inner side a^2 , is mounted a standard c^7 , 100 upon the inner side of which is pivoted a circular disk c^8 , which rotates upon said pivot. To the inner lower side of the disk c^8 , near its periphery is pivoted one end of an operating rod c^9 , the other end of which rod is pivotally connected with the inner side of the sectional plate c^4 , at a point equi-distant from the upper and lower longitudinal edges of said plate. To the same side of the disk c^8 , 105 and in rear of the pivotal point of the lever c^9 , on said disk is pivotally attached near the periphery of said disk one end of an elevating rod c^{10} , the other lower end of which rod is connected with the inner side of the sectional plate c^5 , at a point near one end and equi-distant from its upper and lower longitudinal edges. To the inner side of the disk c^8 , is also pivotally attached in rear of the pivotal point 110 of the rod c^{10} , and near the periphery of said

disk one end of an elevating rod c^{12} , the other end of which rod extends downwardly to a point between the upper and lower longitudinal edges of the plate c^6 , and is pivotally attached to said plate. To the inner side of disk c^8 , above the pivotal point of said disk on the standard c^7 , is attached flatwise one end of a horizontal lever c^{14} , the other end of which lever extends rearwardly toward the standard d' , of the frame D. Upon the standard c^7 , is attached a bolt socket c^{15} , in which is a bolt c^{16} . In the periphery of the disk c^8 , are notches c^{17} , for the reception of the lower end of the bolt c^{16} .

Upon the forward ends of the floats A. A' are the wings W. W'. The wing W. is constructed as follows:—To the top a' , of the float A. is attached rigidly one end of bar w , the other end of which bar extends outwardly at an angle to the inner side a^2 , of float A. and forwardly a considerable distance for the control of the current of water. In the under side of the bar w , is a longitudinal groove w' . To the bottom a^4 , of the float is attached one end of a horizontal bar w^2 , which is also grooved longitudinally in its upper side and is placed in a parallel position with and beneath the bar w . The width of the grooves w' , is such as to admit the parallel position of the plates as hereinafter described. In the grooves w' , of the upper bar w , is inserted from the outer end of said bar one end of a flat plate w^3 , which is narrow in width, and the lower end inserted in the groove w' , on the lower bar w^2 , and said plate moved edge-wise against the forward end of the floats A. A similar plate w^4 , is also placed within the grooves w' , of bars w , w^2 , and with its vertical inner edge overlapping the outer vertical edge of the plate w^3 . A plate w^5 , similar to plate w^4 , is also placed in the grooves w' , of bars w , w^2 , and its inner vertical edge caused to overlap the outer edge of the plate w^4 . In each plate w^3 , w^4 , w^5 , near the upper ends of said plates are the horizontal slots w^6 , which extend to within a short distance of the vertical edges of said plate and register in position one with another. In the lower ends of said plates are similar horizontal slots w^7 . In the slots w^6 , of the overlapping plates w^3 , w^4 , are pivots w^8 , which are provided with heads upon both ends. In the registering slots of the plates w^4 , w^5 , are similar pivots w^9 , which permit the plates to slide over the other. Upon the top a' , of float A. at the forward end of said float is a standard Y. upon the inner side of which is pivotally attached a drum y, upon the periphery of which drum is the operating radial arm y' . Upon both ends of the bar w , and upon the inner sides of said bar are the pulleys w^8 , w^9 . To the inner side of the plate w^5 , near the upper end is attached one end of a rope y^2 , the other end of which rope is thence passed over the pulley w^8 , on the inner end of bar w , thence around the drum y , thence to and over the pulley w^9 , on the forward end of the bar w , and thence at-

tached to the outer vertical edge of the plate w^5 . Upon the other float A', is a similar wing W', which is constructed in precisely the same manner and operated by a similar drum and rope as described upon the float A.

In the operation of the motor, the lever w^4 , on the disk c^8 , is operated to raise the sectional plate of the sluice gate C⁸, seen in dotted lines, Fig. 1, and the current enters the sluice a^0 . The position of the buckets which are submerged in the water are in a closed position as seen in dotted line in Fig. 1. and retained by the bucket closing rod V. The pawl s^5 , is raised from the notches in the ratchet wheel s^4 , and the rod V. permitted to descend and the plates o^8 of the buckets fall into a vertical position and the action of the water follows the buckets, passing rearwardly and over the sprocket wheels M. M. and in a position above the said wheels the ends of the buckets are open and the water passes through and unobstructed thus overcoming the resistance abreast of the current. In passing the curved line of the rod u^2 , of the shield U, the buckets are prevented from filling and consequently are subjected to irregular action of the current which action is prevented until the bucket has passed below the shield U. and the lower plate u' , of said shield at which point the bucket fills and the plate o , forming the bottom of the bucket, resists the water and the bucket moves rearwardly under the hydraulic pressure of the current. The force of the water which impinges upon the buckets depending from the sprocket chain has a tendency to bend the chain and this action is counteracted by the auxiliary buckets P. which also receive the power of the current of water and serve with the buckets O, to equalize the strain upon the chain and facilitate its action. The rotary action of the buckets communicates rotary movements to the shafts F. and G. and the power transmitted to the pulley on shaft F. and the cable on same pulley, and the entire power of the motor obtained, which power may be communicated to the other shafts in any suitable manner upon or at a distance from the motor. When it is desired to lower the frame D. carrying the motor below the level of the floats or carriages, the levers K. K. are operated to elevate the bar H. H. a slight distance, the pins on said bars are withdrawn and the pins placed in a perforation above and the lever raised so as to permit the weight of the frame to come upon said pins and this action is repeated until the proper depths of the buckets are obtained, in which position the ice or any obstruction in the river will pass over the shield U. and the buckets be guarded from injury, so that our motor is adapted for use in winter, beneath the ice.

In raising the motor the action of raising the bar H. is repeated and the pins drawn out and inserted at points one below another. The current which meets the plate u' , concentrates the power upon the buckets and additional

power is obtained. When the current is weak the wings are extended as seen in Fig. 1. When the current is too strong the drum y , is operated to draw the plates w^3, w^4, w^5 , rearwardly, which plates are moved into a parallel position and near the forward end of the floats, the current then passing beneath the bars w, w^2 , and diverted by the curved end of the floats A. A'. The force of the water 5 may be diminished by forcing the sectional plates of the sluice gate downwardly, and the stop bolts retain the plates in position after the adjustment of said sluice gate.

Having fully described our invention, what 15 we now claim as new, and desire to secure by Letters Patent, is—

1. In hydraulic motors consisting of side floats connected with each other and having an intermediate sluice, a movable frame in 20 said sluice having water actuated devices thereon and vertical side bars connected with said frame, standards upon said floats having each a swinging fulcrum and a lever on said fulcrum and engaging devices on said bars 25 for said levers, and movable supports on said bars resting upon the said floats for the purpose described.

2. In hydraulic motors consisting of side floats connected with each other and having 30 an intermediate sluice and a frame for said motor within said sluice having side bars connected with and supported by said floats of transverse driving shafts having horizontal grooved supports upon and at each end of 35 said frame sprocket wheels upon said shafts and sprocket chains extending over the sprocket wheel on one shaft and also over the sprocket wheel upon the other shaft and vertical shifting levers fulcrumed upon said 40 frame and having their lower ends engaging with and moving said shafts in said grooved supports for the purpose described.

3. In a rotary hydraulic motor having an 45 endless traveling conveyer, a water actuated bucket having its end plate connected with said conveyer provided with downwardly extended outer ends, said ends having pivots and a back to said bucket fulcrumed upon 50 said pivots below the upper longitudinal edge of said back plate, for the purpose described.

4. In a rotary hydraulic motor a water actuated bucket having a swinging back extending in one direction and an auxiliary bucket having its back extending in an opposite direction, and a stop upon the back of one 55 bucket extending to the back of the other bucket, as and for the purpose described.

5. In a rotary hydraulic motor, the combination of water actuated buckets having oppositely extended swinging backs and an intermediately connected end and an extension 60

device for the back of one of said buckets connected with the back of the other bucket, substantially as and for the purpose described.

6. In a rotary hydraulic motor a water actuated bucket having downwardly extended outer ends and pivots on said outer ends, and a swinging back fulcrumed upon said pivots and adapted to make contact with the inner side of said end, an auxiliary swinging plate 65 connected with said end and extending in an opposite direction to the back of said bucket, a guide opening in said end plate and a rod pivoted to the back of said bucket and extending through the guide opening in said end 70 plate and adapted to make contact with the back of said auxiliary plate for the purpose described.

7. In hydraulic motors the combination of side floats connected with each other and having 80 an intermediate sluice a motor carrying frame within said sluice supported by said floats and driving shafts on said frame having sprocket wheels an endless conveyer extending over the sprocket wheels on one shaft 85 and over the sprocket wheels on the other shaft water actuated buckets on said conveyer each having a hinged back, a rod within said sluice beneath said hinged backs and means on said frame for elevating said rod for the 90 purpose described.

8. In hydraulic motors consisting of side floats connected with each other and having an intermediate sluice, the combination of separate sluice closing plates pivoted to the 95 sides of said floats, operating rods connected with each plate and an eccentric upon said floats operating said rods simultaneously, for the purpose described.

9. In hydraulic motors consisting of side 100 floats connected with each other and having an intermediate sluice, of wings upon and extending outwardly and beyond the forward ends of said floats and having sliding plates therein, for the purpose described.

10. In hydraulic motors consisting of side 105 floats connected with each other, and having an intermediate sluice, of wings upon and extending outwardly and beyond the forward ends of said floats, sliding plates within said 110 wings and means for operating said plates, for the purpose described.
